UNITED STATES PATENT OFFICE.

ALFRED GRIEB, OF ELIZABETH, NEW JERSEY, ASSIGNOR TO THE SINGER MANUFACTURING COMPANY, A CORPORATION OF NEW JERSEY.

SMOCKING DEVICE FOR SEWING-MACHINES.

1,255,526.

Specification of Letters Patent.

Patented Feb. 5, 1918.

Application filed November 23, 1916. Serial No. 132,945.

To all whom it may concern:

Be it known that I, ALFRED GRIEB, a citizen of the United States, residing at Elizabeth, in the county of Union and State of New Jersey, have invented certain new and useful Improvements in Smocking Devices for Sewing-Machines, of which the following is a specification, reference being had therein to the accompanying drawings.

10 This invention relates to sewing machines of the type adapted to form detached groups of fastening stitches and has for an object to provide a machine of this type with improved work-holding mechanism designed 15 to permit quick, easy and accurate manipulation of the fabric during the production of honey-combed or smocked work wherein the base portions of a series of parallel closely arranged tucks are secured together at intervals by spaced groups of fastening stitches, the groups of stitches of adjacent rows being disposed in staggered relation.

20 The invention has for another object to provide a smocking attachment wherein the various parts are carried by a common support which is adapted to be mounted upon the bed-plate of a sewing machine.

25 Another object of the invention is to provide means for jogging the attachment laterally of the needle-path in timed relation with the reciprocations of the needle.

30 Another object of the invention is to provide the attachment with a fold-positioning blade formed with an elongated guiding tongue adapted to engage a plurality of previously formed groups of tying stitches and assist in accurately positioning the work in the form of a smooth and undistorted fold and in proper position relative to the needle.

40 A further object of the invention is to provide the fold-positioning blade with a straight and unobstructed slot between the elongated guiding tongue and the body of the blade to first receive and subsequently 45 permit the easy escape of the groups of stitches as they are shifted in a direction lengthwise of said tongue.

50 A further object of the invention is to provide the attachment with an upper work-clamping plate which will hold thick or thin work with equal facility and which may be lifted through suitable manually controlled means.

With the above and other objects in view,

as hereinafter more fully explained, the invention is disclosed as embodied in a machine of the well-known button-sewer type constructed substantially in accordance with the disclosure in the patent to J. J. Sullivan, No. 777,564, and comprising a reciprocating needle and a work-holder to which lateral jogging movements are imparted through suitable connections with a controlling cam which carries a tripping point adapted to release the stop-mechanism at the end of a stitching cycle.

55 In the present instance the work-holding mechanism includes a frame-member, the shank of which is detachably secured to the forward end of the lower clamp-actuating 60 bar common to machines of the type above referred to. This frame is formed with an upstanding boss which is apertured to receive one leg of an inverted U-shaped hanger, to the other leg of which is secured 65 the shank of a forwardly disposed T-shaped fold-positioning blade which is arranged substantially in a horizontal plane with its transversely extending operative head disposed above the usual fabric-supporting 70 plate secured to the forward end of the clamp-actuating bar. The frame is also formed with a rearwardly offset boss apertured horizontally to receive a bearing pin 75 upon which is pivotally mounted the shank 80 end of a T-shaped clamping plate, the clamping head of which is disposed above and substantially parallel with the active portion or head of the fold-positioning 85 blade. The forward edge of the clamping 90 plate is notched, centrally of its length, to receive the needle and is provided on opposite sides of said notch with series of graduations and suitable indicating pointers facilitating the accurate spacing and arrangement of the groups of stitches.

95 In the accompanying drawings, Figure 1 is a side elevation of a machine embodying the invention. Fig. 2 is a reverse side elevation of the machine. Fig. 3 is a perspective view showing the attachment in working position on the bed-plate of the machine. Fig. 4 is a plan view of the attachment. Fig. 5 is a detail plan view of the operative portion or head of the fold-positioning blade. Fig. 6 is a cross-section taken on the line 6-6 of Fig. 4 with the work-clamp in its lower or clamping position. Fig. 7 is a

similar view showing the clamp-plate elevated, and Figs. 8 and 9 are front and reverse side views of a sample of the work produced by the machine.

5 In the preferred embodiment of the invention, as illustrated, the machine comprises the bed-plate 1, standard 2 and arm 3, terminating in the head 4 in which is journaled the needle-bar 5 carrying the needle 6 adapted to coöperate with a loop-taker of any well-known form, such as a shuttle, which may be mounted to oscillate in the raceway 7. The needle-bar is reciprocated by the usual connections with the main-shaft 8 journaled in the arm 3 and carrying at its rearward end the tight and loose pulleys 9 and 10, respectively.

The main-shaft also carries a worm 11 meshing with a gear 12 on a cross shaft 13 having an outboard projection on which is mounted the usual controlling cam-wheel 14 acting to impart operative movements to the usual work-clamp supporting bar 15 through the link and lever connections common to 25 machines of the type disclosed in said Sullivan patent. Certain of these connections for vibrating the clamp-bar 15 laterally commonly take the form of a cam-actuated lever 16 connected by a link 17 to one arm 18 of 30 a bellcrank-lever whose other arm 19 is connected by a bowed link 20 to a slide-block 21 mounted at the under side of the bed-plate 1 and secured to the clamp-bar 15 by suitable bolts, one of which is shown at 22. 35 For reciprocating the clamp-bar 15 longitudinally it is common to employ the cam-actuated lever 23 having a slotted arm 24 in which is fitted in a manner well-known the block 25 embracing the upright pin 26 40 fixed to the clamp-bar 15. In the present instance, the block 25 is shown adjusted to a position concentric with the axis of the lever 23 for the purpose of rendering the vibrations of said lever ineffective. The controlling cam 14 also acts to trip the usual starting and stopping lever S into action to stop 45 the machine at the end of a stitching cycle and is provided with a thread-cutter controlling cam-slot 27 which, in practice, acts 50 through the lever 28 and cutter-bar 29 to impart the first stage cutting movements to the usual thread-cutter, not shown, the second stage movement of which is received from the overthrow of the stop-lever S when the 55 latter is tripped into action. As all of the foregoing construction is well-known and fully described in said Sullivan patent it is deemed unnecessary to more fully describe the same herein.

60 Mounted at the forward end of the clamp-bar 15 by means of the usual dowel-pins 30 and bolt 31 is the fabric-supporting plate 32 having a suitable needle-aperture 33. The plate 32 is quite thin and is adapted to 65 slide upon the throat-plate p during the

operation of the machine. Since the shank-end 34 of the plate 32 is offset above the plane of the work-engaging surface of said plate the latter is deeply notched at 35 to clear the fold-positioning blade 36 to be 70 described.

Secured to the clamp-bar 15 by screws 37 is the under cut shank 38 of the attachment frame 39 which is formed with an upstanding boss 40 apertured to receive one leg 41 75 of an inverted U-shaped hanger comprising the inverted L-shaped rod 42 and the depending arm 43 whose split upper end 43' is clamped about the overhanging free end of the rod 42. The lower end of the arm 43 80 is extended laterally at 44 and grooved to form a seat for the shank 36' of the T-shaped fold-positioning blade 36, above referred to, which is secured in said seat by a thumb-screw 45. The fold-positioning blade 85 36 is formed with a fold defining edge 36' and is apertured at 46 to receive the needle. The blade is further formed with a straight slot 47 which leads from the needle-aperture 46 to and through the left-hand 90 extremity of the operative head of said blade. The slot 47 defines an elongated guiding tongue 48 which is extended beyond the end of the slot 47 and is adapted to engage two or more groups of tying stitches 95 and assist in alining said groups of stitches with the stitching point, thereby adding materially to the ease and rapidity with which an operator may shift the work to new stitch-receiving positions.

100

In the use of an attachment for producing smocked work it is very desirable that thin fabric be held under the same pressure as thick fabric and to secure the fulfilment of this condition the upper clamp-member 105 of the device is pivotally mounted and pressed downwardly by a separate spring in the following manner. The attachment frame 39 is formed with a rearwardly extending arm 49 terminating in an apertured 110 boss 50 in which is fixedly secured a horizontal pivot pin 51 by means of a set-screw 52. Disposed above the head of the work-engaging portion of the fold-positioning blade 36 is the head of a T-shaped work-clamping plate 53 whose reduced shank 54 extends opposite to the shank 36' of the fold-positioning blade 36 and is undercut to fit over the arm 55 to which it is secured by screws 55'. The arm 55 is formed with a 115 boss 56 which is confined for turning movements upon the pin 51 by the collar 57. A coiled spring 58 surrounds the extension 56' of the boss 56 and has one end 59 extended under the arm 49. The other end 120 60 of the spring 58 extends over a corner 61 projecting from the clamp-plate 53 as shown in Fig. 4.

The head or active portion of the clamp-plate 53 is formed with oppositely directed 130

extensions 62, 62 which are disposed above the similar extensions of the blade 36. The clamp-plate 53 is reduced in thickness at its forwardly disposed edge 63 which forms a 5 guide for positioning the base of the previously formed tuck closely in front of the needle-path but beyond the range of action of the needle. The forward edge portion of the clamp-plate 53 is notched at 64 to receive the needle and this notch is elongated 10 sufficiently to permit the relative jogging movements between the needle and clamp-plate in a direction transversely of the edge 63. The clamp-plate 53 is provided with 15 elongated apertures 65, 65, one at each side of the needle-receiving notch 64, through one of which apertures previously formed groups of fastening stitches may be viewed to enable the operator to place said groups 20 opposite a desired graduation mark shown behind the edge 63 when the spacing between adjacent groups of stitches of the initial row being formed is less than the distance from the notch 64 to the end 66 of the 25 tuck-positioning edge 63. The upper end of the upstanding arm 67 which is threaded into the clamp-plate 53 is extended laterally into overhanging relation with a lateral extension piece 68 carried by the usual 30 presser-bar 69 whose upper end is connected to the treadle-operated lever 70. Movement of this lever serves to lift the forward portion of the clamp-plate 53 and swing it 35 upwardly about the pivot-pin 51.

35 In the operation of the device, when the work-clamping plate 53 is lifted, the fold-positioning blade 36 springs upwardly to the position shown in Fig. 7 wherein said blade is spaced above the work-supporting plate 32. The fabric is inserted between the plate 32 and blade 36, and the edge-portion is bent 40 back over the fold-defining edge 36* of said blade. The work-clamping plate 53 is then lowered and acts to clamp the fabric against 45 the lower and upper surfaces of the blade 36, as shown in Fig. 6. The machine is now caused to run through a stitching cycle and forms a group of stitches at the desired point. The work is then released and the 50 group of stitches is shifted along the slot 47 into registry with the desired one of the space indicating graduations on the work-clamp plate. The work is repeatedly clamped and stitched in this manner until 55 the initial row of grouped tying stitches has been formed. The tuck defined by this row of stitches is now drawn forwardly over the blade 36 and the base of said tuck is positioned against the edge 63 of the work-clamping plate 53 during the formation of 60 the next row of tying stitches. It is important that the groups of stitches of subsequent rows be spaced midway between adjacent groups of stitches of a preceding row. 65 To insure this arrangement of the tying

stitches, pointers 71, 71 are provided, one of which may be shifted to indicate a graduation mark of one-half the value of that followed in spacing the stitches of the initial row. The values of these graduations are 70 directly proportional to their respective distances from the needle-hole. In forming the tying stitches of the second row the work is positioned so that an adjacent group of 75 stitches of the previous row is stationed opposite the pointer. When the work is so positioned the group of stitches being formed will take a position halfway between the adjacent groups of stitches in the previously formed row. It will be noted that 80 the clamping plate 53 is extended toward the right as well as toward the left of the needle-notch 64. By substituting a reversely formed fold-positioning blade for that shown, the work may be fed toward the 85 right, as may sometimes be desirable. The active portions of the fold-positioning blade and work-clamping plate are purposely arranged diagonally of the clamp-actuating bar 15. This arrangement permits of the 90 free manipulation of the work about the fold-positioning blade without interference by the frame 39 or bar 15 and also permits the use of a simple construction for supporting said blade and plate. 95

The particular embodiment shown and described is obviously susceptible of material modification both in the form and arrangement of its various parts, within the scope of the invention. The invention is not therefore to be considered as limited to the exact structure shown and described. 100

Having thus set forth the nature of the invention, what I claim herein is:—

1. In a sewing machine, the combination 105 with a frame and stitch-forming mechanism incorporated in said frame and including a reciprocating needle, of a fold-positioning blade extending on opposite sides of the needle-path and cut away to receive the 110 needle, a fold-clamping plate, a support for said blade and plate, and means for vibrating said support relatively to said frame and laterally of said needle.
2. In a sewing machine, the combination 115 with a frame and stitch-forming mechanism incorporated in said frame and including a reciprocating needle, of a work-supporting plate, a work-clamping plate, a fold-positioning blade interposed between said plates, 120 a support carrying said plates and blade, and means for vibrating said support relatively to said frame and laterally of said needle.
3. In a sewing machine, in combination, 125 a reciprocating needle, a work-supporting plate, a fold-positioning blade, a work-clamping plate, a support for said plates and blade, means for vibrating said support laterally of said needle and manually controlled 130

means adapted to lift said clamping plate to release the work.

4. In a sewing machine, in combination, a frame including a bed-plate, bracket-arm and head, stitch-forming mechanism including a needle-bar journaled to reciprocate in said head, and a work-holder mounted for jogging movements on said bed-plate, said work-holder including a supporting bar disposed lengthwise of said bed-plate, an arm mounted on said bar, a fold-positioning blade carried by the free end of said arm and having an operative edge disposed adjacent the stitching point and inclined to the direction of the length of said bar, and a work-clamping plate carried by said bar and disposed above said blade.

5. A smocking attachment for sewing machines comprising, a support adapted to be mounted above the bed-plate of the sewing machine, an arm carried by said support, superimposed fabric-supporting and clamping plates mounted on said support and a fold-positioning blade carried by said arm and positioned between said plates, said fold-positioning blade being cut away to receive the sewing machine needle.

6. A smocking attachment for sewing machines comprising, a support adapted to be mounted for lateral movement over the bed-plate of the sewing machine, an overhanging arm carried by said support, superimposed fabric-supporting and clamping elements mounted on said support, and a fold-positioning element carried by said arm and positioned between said fabric-supporting and clamping elements said fold-positioning element being cut away to receive the sewing machine needle.

7. A smocking attachment for sewing machines comprising, a support adapted to be mounted for movement over the bed-plate of a sewing machine, an inverted U-shaped arm free at one end and at its opposite end joined to said support, superimposed fabric-supporting and clamping members sustained by said support, and a fold-positioning

blade carried by said arm and positioned between said plates.

8. A smocking attachment for sewing machines comprising, a work-support, a clamping member opposed to said support, and a fold-positioning blade interposed between said support and clamping member, said blade including an elongated fold-guiding tongue projecting beyond the body of the blade whereby said tongue may engage a plurality of groups of tacking stitches, and whereby the work may be readily shifted longitudinally of said tongue without dis-tortion.

9. In a smocking attachment, a fabric support, a slotted fold-positioning blade, a pivotally mounted work-clamping plate, and a spring independent of said clamping plate and acting on the latter to urge it toward said support.

10. A smocking attachment for sewing machines comprising, a supporting bar, a fabric-supporting plate and an attachment frame each carried at one end of said bar, a fabric-clamping plate pivoted to said frame on an axis inclined to said bar and having a fabric-engaging edge substantially parallel to said axis, and a fold-positioning blade carried by said frame and disposed between said fabric-supporting and work-clamping plates.

11. A smocking attachment for sewing machines comprising, a fold-positioning blade and a work-clamping member overlying said blade, said blade having a needle-hole, a fold-defining edge, a fold-guiding tongue and a straight and unobstructed stitch-discharging slot leading from said needle-hole in a direction lengthwise of said tongue, whereby the groups of stitches may be removed from the field of action of said blade by a shifting movement solely in the direction of the length of said tongue.

In testimony whereof, I have signed my name to this specification.

ALFRED GRIEB.
